DISPLAY PLAQUE FOR VEHICLES

Clifford W. McLoud, P.O. Box 16, Jackson's Gap, Ala.

Filed June 29, 1959, Ser. No. 56,583

Term of patent 14 years

(Cl. D29—11)

FIG. 1.

FIG. 2.

The dominant features of my design are shown in full lines.

I claim:

The ornamental design for a display plaque for vehicles, as shown and described.
